UNITED STATES PATENT OFFICE.

GEORGE E. STEVENS, OF LACONIA, NEW HAMPSHIRE, ASSIGNOR TO
FRANK E. BUSIEL, OF SAME PLACE.

KNITTING-MACHINE.

SPECIFICATION forming part of Letters Patent No. 630,784, dated August 8, 1899.

Application filed March 6, 1897. Serial No. 626,190. (No model.)

To all whom it may concern:

Be it known that I, GEORGE E. STEVENS, of Laconia, county of Belknap, and State of New Hampshire, have invented an Improvement 5 in Knitting-Machines, of which the following description, in connection with the accompanying drawings, is a specification, like letters on the drawings representing like parts.

This invention has for its object the production of a machine by which to knit tubular fabric strengthened by independent warp and weft put into the fabric between the knitting-threads.

The machine herein to be described is adapted to knit the fabric described in my application Serial No. 622,602, filed February 9, 1897.

Herein the knitted fabric is put together by cylinder and dial needles of a knitting-machine, and coöperating with these needles I employ suitable devices to present the warp-threads and lay the weft-threads in position to be incorporated into the fabric by the knitting-threads.

Figure 1, in side elevation, represents a sufficient portion of a knitting-machine containing my present improvements to enable my invention to be understood; Fig. 2, a partial section enlarged below the dotted line α , Fig. 1; Fig. 2^a, a section of the fabric, and Figs. 3 and 4 show in detail parts of the machine to be described.

The framework is composed, essentially, of a base A, uprights A', and a stationary top 35 yoke A². The base A has erected on it a stand B, herein shown as a cylinder of sufficient size to contain within it the usual take-up mechanism B', the upper end of the cylinder having connected to it by suitable screws B² the lower 40 end of a needle-cylinder B³, the top of said stand about said needle-cylinder being recessed, as shown in Fig. 3, for the reception of a toothed ring C, attached by suitable screws C' to a cam-cylinder C², the said cam-cylinder having inside of it suitable cam-grooves to reciprocate the series of cylinder-needles placed in the grooves of the needle-cylinder. Coöperating with the cam-cylinder and its needles is a dial-plate D, having usual 45 grooves for the reception of a series of dial-needles, the said dial-needles being operated,

in conjunction with the cylinder-needles, to knit a tubular rib fabric by a dial cam-plate D', it having at its under side usual grooves to receive the butts of the dial-needles.

The needle-cylinder, cam-cylinder, the dial-needle plate, and the dial cam-plate are but partially shown, as in practice they are and will be of usual construction commonly found in knitting-machines for knitting rib circular work—as, for instance, in United States Patent No. 292,490, dated January 29, 1884—and therefore the particular detailed construction of these well-known devices need not be herein further described, only to say that the usual cylinder and dial needles will in practice be supplied with knitting-threads α^2 , taken from a suitable spool or spools α , according to whether one or two feeds are employed, the said knitting-threads being passed through eyes α' in suitable thread-guides α^2 , supported, as herein shown, by a movable toothed ring α^3 , which is rotated in unison with the cam-cylinder, as will be hereinafter described, said threads being knitted to form a rib-stitch tube. I introduce into this knitted tube as it is being made on the machine two sets of longitudinal warp-threads b b' , and between the said warp-threads a central or splitting weft thread g^2 , and also at the outer side of said 80 two warp-threads a second weft-thread h , and at the inner side of said two warp-threads a third weft-thread b^3 .

The warp-threads b , taken from suitable bobbins c , are mounted on a ring c^2 , led under 85 and through a ring c' , sustained at the lower ends of arms depending from a plate c^4 , fast with relation to the framework, and thence over a guide-ring c^5 , having a series of uprights, as c^6 , between which the said warp-threads pass on their way to the fabric, said warp-threads entering the needle-cylinder at its top and between said needle-cylinder and the edge of said dial-needle plate. These warp-threads b go between the cylinder-needles and occupy a position intermediate the dial-needles.

The warp b' , taken from bobbins d , supported on a ring d^2 , pass over a ring-guide d' , sustained at the lower end of arms d^2 , fixed 100 to a stationary ring or plate d^3 , and from said ring d' said warps b' pass through a guide-

notch inside of a gathering-ring d^4 , mounted at the lower ends of arms d^5 , also fixed to the underside of said plate d^3 . (See Figs. 1 and 3.) These warp-threads b' are led to the fabric inside the needle-bed and between the top of said bed and the dial-needle plate, and they stand between the dial-needles and in line with the cylinder-needles. To prevent these warp-threads b' from lateral movement or 10 from being displaced from their proper grooves in the ring d^4 , I place inside said ring a stop-ring e .

The dial-needle plate is supported by the lower end of a rod e' , fixed at its upper end 15 in the yoke A^2 .

The dial cam-plate is fixed to the lower end of a sleeve e^3 , in turn fastened at its upper end by a screw e^4 to the lower end of a hub e^5 , having extended upwardly from it a series of 20

arms e^6 , fixed to a toothed ring f , having at its lower side a short hub (see dotted lines, Fig. 1) which enters a groove in the top of the plate d^3 , said groove forming a guide and bearing for said toothed ring, the said ring 25 being actuated from a toothed gear f^2 at the upper end of a shaft f^3 , having at its lower end a bevel-gear f^4 , which is engaged and rotated by a bevel-pinion f^5 , fast on the main shaft E , the same having any suitable fast 30 and loose pulleys.

The bobbins carrying the knitting-threads are secured on the toothed ring a^3 , and said ring is rotated at the same speed as the ring f and in the same direction by a toothed wheel 35 g , also fast on the said shaft f^3 . This ring a^3 , besides carrying the knitting-threads, is also provided with one or more bobbins g' , according to the number of feeds, which bobbins are provided with what I designate as the "central" or "splitting" weft g^2 , (see Fig. 2^a), said weft g^2 being led into and delivered from suitable thread-guides g^3 , the delivery ends of said thread-guides occupying a position between the inner and outer warps, so that said weft-thread is laid between said warps, as shown 45 in Fig. 2^a.

The outside weft h is taken from a bobbin h' , which is contained in a bobbin-carrier h^2 , shown as a yoke fixed to and extending below 50 the skirt or horizontal lower extension of the needle cam-cylinder. This outer weft, one or more being used, according to the number of feeds, will be subjected to the action of a suitable tension device h^3 , and from said tension device it passes over the ring c' and 55 through the outer-weft guide h^4 , it having its delivery end located close to and a little below the upper end of the needle-cylinder, (see Fig. 4,) so that said outer-weft thread will be 60 laid against the outside of the warps b at the knitting-point, the said needle-cylinder being preferably cut away at its outer side near its top to afford a space in which the said thread-guide may travel, the said thread-guide being 65 also below the horizontal plane in which the dial-needles reciprocate in knitting.

The inner-weft thread b^3 on bobbins b^4 is led

through an eye m , fast to the ring f , and thence down inside the circle of warp-threads b' and through suitable thread-guides m' , fixed to the 70 dial cam-plate, as best shown in Fig. 2, said thread-guides delivering their weft-threads against the inner side of the inner-warp threads b' , close to the knitting-point and preferably at a point between the two thread-guides g^3 and h^4 , the said inner-weft thread b^3 being presented at the edge of the dial cam-plate at the point where the said dial-needles are retracted to draw new loops through old loops on their shanks, and the said dial-needles when again pushed fully out to take knitting-thread passing above the said inner-weft thread. In this way the knitting-threads connect and bind together in one solid fabric the warp and weft threads, as best shown in 85 Fig. 2^a.

The toothed ring C of the cam-cylinder is engaged by a pinion n at the upper end of a shaft n' , provided at its lower end with a bevel-pinion n^2 , which is engaged and rotated 90 by a bevel-gear n^3 , fast on the main shaft E .

The cam-cylinder, dial-needle cam-plate, and the rings a^3 and f are rotated at the same speed.

I have herein shown the inner end of the 95 shaft E as provided with a cam o , which will actuate any usual or suitable pawl which will operate the second or feed take-up wheels p , of usual construction.

I may employ any usual rib-knitting devices, my invention consisting in combining with such usual devices the warp and weft presenting means described.

While I desire to use two sets of warps, yet this invention is not at all times limited to 105 such use, for I may dispense with either set of warp-threads and with the filling-thread that crosses that warp at its outer side to bind it into the rib-knitted fabric.

By using the central or splitting weft and 110 omitting either of the other two weft-threads and using the warp of different-colored yarn and using the weft of the same or different color I may knit fancy tubes.

Having described my invention, what I 115 claim, and desire to secure by Letters Patent, is—

1. In a knitting-machine having means for actuating two sets of needles to knit a ribbed fabric, the combination with said knitting devices of means to deliver a separate set of warp-threads upon each side of said ribbed fabric between the vertical lines of stitches thereof, means to retain said warp-threads in position, and means to lay a weft or filling thread or threads between and splitting said sets of warp-threads, substantially as described.

2. In a knitting-machine having means for actuating two sets of needles, to produce a 130 ribbed fabric, the combination with said knitting devices of means to deliver a separate set of warp-threads upon each side of the said ribbed fabric between the vertical lines of

stitches thereof, means to lay weft or filling threads outside the said sets of warp-threads in position to be bound by the loops of knitting-yarn that are formed by the needles, and 5 means to lay a weft or filling thread or threads between said sets of warp-threads, substantially as described.

3. In a knitting-machine having means for actuating two sets of needles to produce a 10 ribbed fabric, the combination with said knitting devices, of means to deliver a separate set of warp-threads upon each side of said foundation fabric between the vertical lines of stitches thereof, means to lay weft or filling 15 threads outside of said sets of warp-threads, and to be bound by the knitting-yarn, and means arranged between said sets of warp-threads to deliver the knitting-yarn and to deliver a weft or filling thread both between 20 said sets of warp-threads, substantially as described.

4. In a knitting-machine having means for actuating cylinder and dial needles to knit a ribbed fabric, the combination with said knitting 25 devices of an outer-warp-guiding ring surrounding the upper end of the needle-cylinder, the said ring guiding and presenting a series of outer warps between the needles of the needle-cylinder, said warp-threads entering the needle-cylinder between its top 30 edge and the circumference of the dial-needle plate, a weft-thread guide, and means to move it in unison with the cam-cylinder to deliver a weft-thread against the outer side of said 35 warp-threads, substantially at the knitting-point, and a central or splitting weft guide to carry a central or splitting weft, and means to actuate said splitting-weft guide, substantially as described.

40 5. In a knitting-machine having means for actuating cylinder and dial needles to knit a ribbed fabric, the combination with said knitting devices of an inner-warp collecting and guiding ring located above the dial-needle plate and presenting a series of inner warp-threads between the dial-needles, said warp-threads entering the said needle-cylinder between its top and the circumference of the 45 said dial-needle plate, and a weft-thread guide and means to move it in unison with the cam-cylinder to deliver a weft-thread against and across said warp-threads, the knitting-threads holding said weft and warp threads into the 50 rib-knitted fabric, and a central or splitting weft guide to carry a central or splitting weft, and means to actuate said splitting-weft guide, substantially as described.

6. In a knitting-machine having means for actuating cylinder and dial needles to knit a 60 tubular ribbed fabric, the combination therewith of an outer-warp-guiding ring surrounding the upper end of the needle-cylinder; an inner-warp-guiding ring located above the dial-needle plate, the outer ring presenting its warp-threads between the needles of the 65 needle-cylinder, and the inner guiding-ring its warp-threads between the plate-needles,

both sets of said warp-threads entering the space between the said needle-cylinder and dial-needle plate, three thread-guides for 70 outer, inner and splitting weft threads, and means to operate said weft-guides, substantially as described.

7. In a knitting-machine, the following instrumentalities, viz: a needle-cylinder to contain cylinder-needles, a surrounding cam-cylinder to actuate said cylinder-needles, a dial-needle plate to contain dial-needles, a dial-needle cam-plate to actuate said dial-needles, means to operate said dial-needle 75 cam-plate, a toothed ring provided with downwardly-extended thread-guides to supply threads to the cylinder and dial needles, a support for said toothed ring located above said dial-needle plate, a driving-shaft, two independent shafts actuated by said driving-shaft, said two independent shafts carrying gearing to rotate said cam-cylinder and said toothed ring in unison in the same direction and a weft-thread guide also carried by said 80 toothed ring, substantially as described.

8. In a knitting-machine, the following instrumentalities, viz: a needle-cylinder to contain cylinder-needles, a surrounding cam-cylinder to actuate said cylinder-needles, a dial-needle plate to contain dial-needles, a dial-needle cam-plate to actuate said dial-needles, means to operate said dial-needle 95 cam-plate, a toothed ring provided with downwardly-extended thread-guides to supply 100 threads to the cylinder and dial needles, a support for said toothed ring located above said dial-needle plate, a driving-shaft, an outer-warp-guiding ring surrounding the upper end of the needle-cylinder and supporting 105 a series of outer warps, and an inner-warp-guiding ring located above the dial-needle plate and supporting a set of inner warps, said outer warps being presented between the needles of the needle-cylinder 110 and the inner warps between the plate-needles, both sets of said warp-threads entering the needle-cylinder in the space between the top of said cylinder and the said dial-needle plate, combined with a splitting-weft-thread 115 guide attached to said dial-needle cam-plate, said toothed ring also having means to hold and present a supply of splitting-weft thread 120 between the said inner and outer warps, substantially as described.

9. In a knitting-machine, the following instrumentalities, viz: a needle-cylinder containing needles and actuating means therefor, a needle-dial containing needles and actuating means therefor, said cylinder and dial 125 needles to coöperate in producing a ribbed fabric, warp-guiding devices to deliver separate sets of warp-threads upon opposite sides of the ribbed fabric produced by said needles, weft-thread devices to deliver weft-threads outside and to bind said warp-threads 130 to said fabric, a ring-like member arranged between the warp-threads delivered to the needles by said warp-guiding devices, means

to rotate said ring, and a filling-thread guide and a knitting-thread guide arranged on said ring to deliver their respective threads between said sets of warp-threads, substantially 5 as described.

10. In a knitting-machine having means for actuating cylinder and dial needles to knit a tubular ribbed fabric, the combination therewith of an outer-warp-guiding ring surround-
10 ing the upper end of the needle-cylinder and an inner-warp-guiding ring located above the dial-needle plate, the outer ring presenting its warp-threads between the needles of the needle-cylinder and the inner guiding-ring, 15 its warp-threads between the plate-needles, both sets of said warp-threads entering the space between the said needle-cylinder and dial-needle plate, a rotating guide for an outer weft-thread and a rotating guide for an inner 20 weft-thread, and a rotating thread-guide for a central or splitting weft thread, and means to rotate said weft-thread guides simultaneously in unison and in the same direction with the cam-cylinder and dial-needle cam-
25 plate of the knitting mechanism, substantially as described.

11. An organized knitting-machine having two sets of needles, and means to deliver knitting-yarn to the said needles, whereby to 30 produce a foundation-rib fabric, means to

deliver a separate set of warp-threads upon each side of the said foundation-rib fabric between the vertical lines of stitches thereof, and means to lay weft or filling threads outside the said sets of warp-threads in position 35 to be bound by the loops of knitting-yarn that are formed by the needles and between and to split said set of warp-threads, substantially as described.

12. An organized knitting-machine having 40 guides for two sets of warp-threads, carriers to lay weft or filling threads at the outer side of one of the said sets of warp-threads and at the inner side of the other set of warp-threads and between said sets of warp- 45 threads; a carrier or carriers to lay a knitting thread or threads between the said set of warp-threads, and two sets of knitting-needles engaging the knitting thread or threads between the two sets of warp-threads to form 50 a foundation-rib fabric having the warp-threads and weft-threads bound therein, substantially as described.

In testimony whereof I have signed my name to this specification in the presence of 55 two subscribing witnesses.

GEORGE E. STEVENS.
